AUTOMATIC PRINTING DEVICE

Hugh E. Rees, Richmond, Va.

Application September 12, 1931, Serial No. 562,549

3 Claims. (Cl. 101—228)

My invention relates to an automatic printing device and more particularly to such a device used in combination with certain machines, such as folding and cutting machines, and reinforcing machines.

One of the difficulties now experienced in the manufacture of books, is the ascertaining of the front and back end sheets, after they have been treated with the reinforcing slip or strip.

10 The front and back end sheets usually have illustrations thereon, especially children's books, and the folding machine cuts and folds them preparatory to the placing thereon of the reinforcing slip.

15 These sheets are then taken to a machine where reinforcing slips are placed thereon. When the front and back end sheets are thus reinforced, the illustrated part thereof can not be observed unless they are forced open; since such is on the 20 inside of the folded end sheets.

The front and back end sheets are then, respectively, placed on each side of the book contents, and all are stitched together; after which, it is cut to form leaflets, and the end sheets are respectively glued to the front and back of the container; thereby forming the completed book.

When the front and back end sheets are placed on the assembling machine, after they have received the reinforcing slip, there is a chance that 30 the operator of this machine might place the back end sheets into the front end sheet rack, and vice versa with respect to the front end sheets, and if this is done, then in certain cases, it will cause great loss. The inventor has personally seen cases where such a mistake was made, 35 and at least five thousand books had to be reprinted.

For instance, if a front end sheet had printed thereon: "This is the beginning of my story", 40 and the back end sheet had: "This is the end of my story", and the back end sheet was assembled in the front of the book, while the front end sheet was placed in the back of the book, then this would produce an error causing probable loss 45 of all books so made.

In order to prevent such errors, one of the objects of this invention is the provision of a device adapted to print on such sheets a symbol designating the position such sheet is intended to take 50 in a book being assembled. There is also a possibility of placing the wrong end sheets in the wrong book, and the invention also overcomes this mistake.

Another object of this invention is the provision 55 of a device adapted to enter into combination

with a folding machine, or reinforcing strip machine, so as to print symbols on said sheets.

Other objects and features will more fully appear from the following description and accompanying drawings, in which; Fig. 1 is a front view 60 in elevation; Fig. 2, a side view; Fig. 3 a side view of a roller, and Fig. 4, a sectional view in elevation showing the invention attached to, and in combination with, a machine.

Referring to the drawings, a bracket 1 is provided with slots 2, (one of which is not shown) into which are respectively inserted, axles 3 and 4, adapted to support rollers 5 and 6, rotatable thereon. The axles have heads 7 and ride in the slots, thereby permitting free vertical movement, 70 and the rollers engage one another so that when one is actuated motion is transmitted to the other. Roller 5 is adapted to receive ink from and supply it to roller 6, as will more fully be explained hereinafter.

75 A printing roller 8 is disposed at the end of said bracket and is rotatable on an axle which is secured thereto by a bolt 9 provided with a nut 9.

The roller 8 consists of sections 10 and 11, 80 the former being provided with a male member 12, which is adapted for registration with an aperture 13 in said section 11. The sections are secured together by screws 14, disposed in slots in section 11, and adapted to engage threaded 85 holes 15 in said first named section. The slots in section 11 are partially countersunk so that the screws heads will be flush with the surface of said section, and not project therefrom.

85 Circumferential recesses 16, respectively located on sections 10 and 11 are adapted to accommodate rubber rings 17. A rubber stamp 18 is slipped on section 10 and secured against lateral displacement by a rubber blank 19, adjacent thereto. When said sections are secured 90 together rims 20 and 21 form a recess 22, into which said stamp and blank fit. The stamp may be made of any material, and no restriction is intended by the use of the word "rubber". The blank is of a height equal to that of the 100 stamp so as to minimize wear by roller 6, and sheets, of the latter.

An ink well 23 is secured, by screwing, to the top of said bracket, and may be adjusted to feed ink to a wick 24, located near the ink supply; and depending therefrom so as to touch roller 5, and keep it supplied with ink. As roller 5 rotates ink is drawn thereon from the wick. A thumb screw regulates a pin 25 engaging a 105 nipple 26. A detailed description of the well 110

is not thought necessary since it is in general use, and well known in the art.

The bracket is pivotally connected to a support 27 by a bolt 28 provided with a nut (not shown). Said support 27 resembles, in shape, a chair, and has a back 30 through which a screw 31 is disposed and secured thereto by a nut 32. A spring 33 fits over said screw, one end bearing against a tension nut 32', and the other end, which extends beyond said screw, is seated in an aperture 34, in said bracket.

The support is also provided with a pair of legs 35, one of which accommodates a set screw 36, which is adapted to secure the device to a cross-bar 37 on (in this particular instance) a folding and cutting machine 38, a portion of which, is only shown.

The machine 38 is provided with a plurality of rollers 39 upon which are respectively mounted, belts 40 that convey and eject the end sheets from said machine. The ejected sheets are deposited into a container, not shown, and then taken to be treated with reinforcing slips.

A roller 41 provided with rubber rings 42, in spaced relation to each other, has adjoining it a roller track 43 upon which a belt is connected, similar to those described for rollers 39. The rings 42 abut rings 17, and transmit motion thereto. The roller 41 is rotatable on an axle 44, and both are substituted for the usual machine roller 39, and secured to the bracket 39'.

The bracket, as heretofore described, is pivotally connected to the support, and the spring 33 tends to force the former downwardly, thereby assuring proper pressure of roller 8 against roller 41 so as to provide a clear symbol. The tension nut 32' may be employed to obtain proper tension. Free axial movement of the bracket is also permitted to compensate for material passing between said rollers, as well as unforeseen complications.

The device functions as follows: As the belt

moves, it actuates roller 41, which is in operative relation with roller 8, and transmits motion thereto. The stamp and blank on roller 8 engages roller 6, and the latter, in turn, engages roller 5. The wick is fed with ink from the well, and spreads it upon roller 5, and such is transferred to roller 6 and supplied to the stamp.

As the end sheets are being conveyed by the belt, they pass between rollers 8 and 41 on rings 17 and 42, and the stamp prints a designating symbol thereon. This invention may be used upon various machines, as for instance; it may be combined with a machine generally used for putting reinforcing strips on the end sheets.

Having described my invention, I claim:

1. The combination in a folding and cutting machine consisting of a support secured to said machine; a bracket pivotally connecting said support, a plurality of ink-rollers mounted rotatably in said bracket; a roller stamp in said bracket in operative relation with said ink-rollers; a roller engaging said roller stamp, and a conveyor belt engaging said last named roller to transmit motion to aforesaid rollers.

2. In a device of the character described consisting of a support, a bracket pivotally connecting said support; a plurality of ink-rollers mounted loosely in said bracket; means for supplying ink to said rollers; a stamp-roller, a roller engaging said stamp roller, and a conveyor belt engaging said last named roller and adapted to be actuated to transmit motion to aforesaid rollers.

3. In a device of the character described consisting of a support, a bracket pivotally connecting said support; a plurality of ink rollers mounted loosely in said bracket; means for supplying ink to said rollers; a stamp roller, a roller engaging said stamp roller and means engaging said last named roller and adapted to actuate same so as to transmit motion to aforesaid rollers.

HUGH E. REES.
